SNAP-ACTION THERMOSTATIC SWITCH

Albert E. Baak, Pacific Palisades, Calif., assignor
to Paul Henry, Los Angeles, Calif.

Application December 30, 1950, Serial No. 203,597

20 Claims. (Cl. 200—138)

1

The present invention relates to mechanisms operating with a snap action and, more particularly, to a snap-action switch for opening and closing electrical circuits. The snap-action switch may be operated by thermostatic means responsive to temperature variations so as to open and close electrical circuits in response to such temperature variations.

A primary object of the invention is to provide an improved snap-action switch and thermostatic operating means therefor.

More particularly, an object of the invention is to provide a snap-action switch having a switch member which is pivotable between two operating positions with a snap action by the resultant of a substantially constant force applied thereto and a variable input force applied thereto, the input force being variable with temperature variations, for example.

Another object is to provide a snap-action switch wherein the included angle between the substantially constant force and the variable input force is greater than 0° and less than 180° so that the resultant of the two forces swings from one side of the pivot axis of the switch member to the other to move the switch member from one of its operating positions to the other, depending upon the magnitude of the variable input force.

Another object is to apply the substantially constant force to the switch member by means of a coil spring acting along a line in close proximity to the pivot axis of the switch member so that the length of the spring is substantially unchanged by pivotal movement of the switch member through a limited angle, whereby to maintain the force applied by the spring substantially constant.

An important object of the invention is to apply the substantially constant spring force and the variable input force to a pivoted actuating member which is operatively connected to the switch member with a lost-motion connection so that the actuating member does not move the switch member until a predetermined pivotal movement of the actuating member has occurred, whereby the actuating member applies an impact force to the switch member to move the switch member suddenly. This insures a clean break of the contacts controlled by the switch member with a minimum of arcing.

Another object is to provide such a snap-action switch wherein the switch member and the actuating member are pivotally connected to a supporting structure for rotation about a common

2

pivotal axis. A related object in connection with one embodiment of the invention is to provide a snap-action switch wherein the actuating member and the switch member are independently pivotally connected to the supporting structure, but by the same pivot means. A further object in connection with such embodiment is to provide a lateral offset between the actuating member and the switch member so that the ends of the actuating member are spaced from the switch member when the actuating member is in an intermediate position with respect to the switch member, whereby to provide a lost-motion connection between the two members.

15 An object in connection with another embodiment of the invention is to provide a switch member which is carried by the actuating member and which is operatively connected thereto by a lost-motion connection.

20 Another important object is to provide a snap-action switch having wiping means comprising two relatively slidable elements for absorbing any kinetic energy tending to cause a contact means of the switch member to bounce off stationary contact means carried by the supporting structure upon engagement of the contact means of the switch member with the stationary contact means. A related object in connection with one embodiment of the invention is to provide such 25 a wiping means which is completely independent of the contact means so that the wiping action which absorbs the kinetic energy does not take place between the two contact means. Thus, the energy absorption of the wiping means remains constant and is unaffected by pitting of the contact means, which is an important feature.

Another object is to provide such a wiping means operating independently of the contact means which includes an element connected to 40 and movable with the actuating member and slidably engaging a surface of the switch member so that the energy-absorbing wiping action takes place between such element and the switch member.

45 Still another important object is to provide resilient means for biasing the contact means of the switch member into engagement with the stationary contact means during pivotal movement of the actuating member in a direction to separate the two contact means until such time as the lost motion between the actuating member and the switch member has been taken up, whereby to insure a clean break of the two contact means and thus minimize arcing.

50 An object in connection with one embodiment

is to provide a snap-action switch wherein the same elements form the wiping means for absorbing kinetic energy and the resilient means for biasing the contact means into engagement.

Another important object is to provide a thermostatic means for operating the snap-action switch mechanism which includes an elongated bimetallic element, and which includes an improved means for calibrating the bimetallic element.

Another object is to provide such a calibrating means which includes a first adjusting screw engaging one end of the bimetallic element and which includes fulcrum means for the bimetallic element intermediate its ends, the fulcrum means including a second adjusting screw. A related object is to provide a fulcrum means which includes, in addition to such second adjusting screw, a fulcrum element engaging the bimetallic element, the fulcrum element and the second adjusting screw engaging opposite sides of the bimetallic element.

Another important object is to provide means for preventing any unusual forces applied to the bimetallic element from excessively stressing the bimetallic element. A related object is to provide a construction wherein the aforementioned fulcrum element is carried by one end of a leaf spring so that the fulcrum element may yield in response to unusual forces applied to the bimetallic element.

Another object is to provide a structure wherein one of the adjusting screws has a pointer connected thereto which is movable over a dial, the pointer having a detent element thereon which is engageable with indicia-forming detent elements on the dial to retain the pointer in various predetermined positions. Thus, the detent elements on the dial also serve as indicia for indicating the position of the pointer relative to the dial, which is an important feature.

Another object is to provide a snap-action switch which includes a minimum number of parts and which includes parts that may be assembled readily. In this connection, an object is to provide a pivot means for the actuating member which merely includes an element having edges disposed in notches in the actuating member.

The foregoing objects and advantages of the present invention, together with various other objects and advantages thereof which will become evident, may be attained with the exemplary embodiments of the invention illustrated in the accompanying drawings and described in detail hereinafter. Referring to the drawings:

Figs. 1 to 4, inclusive, are views diagrammatically illustrating the structure and operation of the snap-action mechanism of one embodiment of the snap-action thermostatic switch of the invention;

Fig. 5 is a front elevation showing the actual construction of the embodiment diagrammatically illustrated in Figs. 1 to 4;

Fig. 6 is an enlarged sectional view taken along the arrowed line 6—6 of Fig. 5;

Fig. 7 is a sectional view taken as indicated by the arrowed line 7—7 of Fig. 6;

Figs. 8 and 9 are enlarged sectional views respectively taken along the arrowed lines 8—8 and 9—9 of Fig. 5;

Fig. 10 is a sectional view on a reduced scale taken along the arrowed line 10—10 of Fig. 6;

Fig. 11 is a fragmentary sectional view taken as indicated by the arrowed line 11—11 of Fig. 6; 75

Fig. 12 is a view similar to Fig. 9, but showing a modification of the embodiment illustrated in Figs. 1 to 11;

Figs. 13 to 16, inclusive, are views similar to Figs. 1 to 4 and illustrate diagrammatically the structure and operation of the snap-action mechanism of another embodiment of a snap-action thermostatic switch of the invention;

Fig. 17 is a sectional view which is similar to Fig. 8, but which illustrates the actual construction of the snap-action mechanism shown diagrammatically in Figs. 13 to 16, Fig. 17 being taken as indicated by the arrowed line 17—17 of Fig. 18;

Fig. 18 is a sectional view taken as indicated by the arrowed line 18—18 of Fig. 17; and,

Figs. 19 and 20 are sectional views taken along the arrowed lines 19—19 and 20—20, respectively, of Fig. 18.

Considering first the embodiment of the invention which is illustrated in Figs. 1 to 11, the general structure and operation of this embodiment will be considered in connection with Figs. 1 to 4 prior to considering the detailed structure thereof. It is thought that this procedure will make the disclosure of the detailed structure much easier to follow.

Referring particularly to Figs. 1 to 4 of the drawings, the snap-action switch illustrated therein is of the double-pole, double-throw type in the particular embodiment under consideration and includes a supporting structure indicated generally by the numeral 21. Included in the supporting structure 21 is a support to which an actuating member 23 and an actuated or switch member 24 are pivotally connected by a common pivot means 25. Thus, the actuating member 23 and the switch member 24 may pivot relative to the supporting structure about the axis of the pivot means 25. It will be noted that the actuating member and the switch member 24 are offset laterally with respect to each other so that the actuating member 23 may pivot relative to the switch member 24 through a limited angle, the ends 26 and 27 of the actuating member being adapted to engage the switch member 24 to limit pivotal movement of the actuating member relative to the switch member. Thus, it will be apparent that there is a lost-motion connection between the actuating member and the switch member, the actuating member being adapted to pivot through a limited angle before one or the other of the ends 26 and 27 thereof engages the switch member. As will be pointed out in more detail hereinafter, this lost-motion connection between the actuating member 23 and the switch member 24 is an important feature of the invention.

The switch member 24 includes a pair of contact means 30 and 31 respectively adapted to engage stationary contact means 32 and 33 carried by the supporting structure 21. In the particular construction illustrated, the contact means 30 and 31 of the switch member 24 are contact bars and the stationary contact means 32 and 33 respectively comprise paired contacts which are spaced apart and which are adapted to be bridged by the contact bars, respectively. Also, as will be apparent, the two stationary contact means 32 and 33 serve as stop means for limiting the pivotal movement of the switch member 24 about the pivot axis provided by the pivot means 25. The paired contacts of the stationary contact means 32 and 33 may be connected in any desired electrical circuit or circuits.

The snap-action switch embodiment under consideration includes means for applying to the actuating member 23 a substantially constant force, represented by the arrow 36, which tends to pivot the actuating member in one direction about the axis of the pivot means 25, i. e., in the counterclockwise direction as viewed in Figs. 1 to 4 of the drawings. As will be discussed in more detail hereinafter, the means for applying the substantially constant force 36 to the actuating member includes a coil spring acting in tension, the coil spring being diagrammatically represented by the broken line 37. As will be noted, the spring 37 is indicated as being connected to the end 27 of the actuating member 23 and as being connected to the supporting structure 21 at a point 38. It will also be noted that the spring 37 extends along a line in close proximity to the axis of the pivot means 25. Consequently, as the actuating member 23 pivots about the axis of the pivot means 25, the end 27 of the actuating member 23 moves substantially on an arc having as its center the point 38 of connection of the spring 37 to the supporting structure 21. Thus, the length of the spring 37 remains substantially constant as the actuating member 23 pivots so as to maintain the spring force 36 substantially constant, which is an important feature.

Also acting on the actuating member 23 is a variable input force, represented by the arrow 41. It will be noted that the input force 41 is applied to the end 26 of the actuating member 23 in a direction such that it tends to pivot the actuating member in a direction opposite to that in which the spring force 36 tends to pivot the actuating member so that the two forces oppose each other, the input force 41 tending to pivot the actuating member in the clockwise direction as viewed in Figs. 1 to 4 of the drawings. Thus, it will be seen that the spring force 36 tends to open the contact means 30 and 32 and close the contact means 31 and 33, while the variable input force 41 tends to close the contact means 30 and 32 and to open the contact means 31 and 33.

In the particular construction illustrated, the input force 41 is applied to the actuating member 23 by a thermostatic means 42, shown as including a bimetallic element 43 connected to the supporting structure 21 at 44.

Considering the general operation of the switch embodiment diagrammatically illustrated in Figs. 1 to 4 of the drawings the position of the switch member 24 is determined solely by the magnitude of the variable input force 41 since the spring force 36 is substantially constant. Thus, the magnitude of the input force 41 determines whether the contact means 30 and 32 are closed, or whether the contact means 31 and 33 are closed. As a starting point, it will be assumed that the input force 41 is small so that the resultant of the spring force 36 and the input force 41 acts to bias the actuating member 23 and the switch member 24 in the counterclockwise direction, as viewed in Figs. 1 to 4 of the drawings, so as to close the contact means 31 and 33.

Now assume that the bimetallic element 43 increases the input force 41 applied to the actuating member 23 to a value such that the resultant of the spring force 36 and the input force 41 swings across the axis of the pivot means 25 and acts to bias the actuating member 23 in the clockwise direction, such an increase in the input force be-

ing due, for example, to an increase in the temperature of the bimetallic element. This condition is illustrated in Fig. 1 of the drawings, the resultant of the spring force 36 and the input force 41 being represented by the arrow 45. As will be apparent, the resultant force 45 acts in the clockwise direction so as to close the contact means 30 and 32 and to open the contact means 31 and 33. Thus, as soon as the input force 41 increases sufficiently to swing the resultant force across the axis of the pivot means 25 into the position occupied by the resultant force 45 in Fig. 1 of the drawings, the actuating member 23 starts to rotate in the clockwise direction, as viewed in Figs. 1 to 4 of the drawings. Because of the lost-motion connection between the actuating member 23 and the switch member 24, the latter member remains stationary until it is engaged by the end 26 of the actuating member. Thus, the contact means 31 and 33 remain closed until the end 26 of the actuating member 23 engages the switch member 24, whereupon the impact of the end 26 of the actuating member on the switch member opens the contact means 31 and 33 suddenly. This sudden breaking of the contact means 31 and 33 minimizes arcing, which is an important feature of the invention.

Thus, as soon as the input force 41 increases to a value sufficient to swing the resultant force across the axis of the pivot means 25 into the position occupied by the resultant force 45 in Fig. 1, the various components of the device move from the positions occupied thereby in Fig. 1 to the positions occupied thereby in Fig. 2. As will be noted by comparing Figs. 1 and 2 of the drawings, even though the input force 41 decreases in magnitude somewhat as the stress in the bimetallic element 43 is relieved in response to movement of the various components from the positions shown in Fig. 1 to those shown in Fig. 2, the distance of the resultant force 45 from the axis of the pivot means 25 increases as the various components move toward the positions shown in Fig. 2. Thus, the effective force applied to the various components increases as they move toward the positions shown in Fig. 2. This insures operation of the device with a snap action, which is an important feature.

Now assume that, with the various components of the device in the position shown in Fig. 2 of the drawings, the temperature of the bimetallic element 43 decreases to an extent sufficient to so reduce the input force 41 that the resultant of the spring force 36 and the input force 41 swings across the axis of the pivot means 25 in the opposite direction so that it tends to bias the actuating member 23 in the counterclockwise direction, as indicated by the position of the resultant force 45 in Fig. 3. As soon as the resultant force 45 crosses the pivot axis in this manner, it causes the actuating member 23 to pivot in the counterclockwise direction, the switch member 24 remaining stationary until the end 27 of the actuating member engages it with an impact force which breaks the contacts 30 and 32 suddenly to minimize arcing. As shown in Fig. 4, even though the input force 41 increases somewhat as the bimetallic element 43 is stressed during pivoting of the various components into the positions shown in Fig. 4, the resultant force 45 swings away from the pivot axis as the various components rotate into the positions shown in Fig. 4 so that the effective force acting to rotate the various components into the positions shown in Fig. 4 continually increases. Again, this causes

the device to operate with a snap action in this direction also.

Thus, the device operates with a snap action in both directions because of the fact that, as the various components of the device rotate toward their new positions when the resultant force 45 swings across the axis of the pivot means 25, the offset of the resultant force continually increases as the various components approach their new positions. Also, because of the lost-motion connection between the actuating member 23 and the switch member 24, the switch member 24 tends to remain stationary until the impact of the actuating member 23 thereon causes it to pivot, thus insuring a clean break of the contact means being opened. Considerable kinetic energy is built up by the actuating member 23 during the interval that the lost-motion connection between the actuating member and the switch member 24 is being taken up so that the impact force applied to the switch member 24 is amply large to insure a clean break of the contact means being opened, which is an important feature of the invention. In order to maintain the contact means 30 and 31 in engagement with the respective stationary contact means 32 and 33 during the intervals that the lost motion in the connection between the actuating member 23 and the switch member 24 is being taken up, a small leaf spring 47 rigidly connected at its midpoint to the midpoint of the actuating member 23 is provided. This spring has ends 48 and 49 which bear against the switch member 24 on opposite sides of the axis of the pivot means 25. Thus, as the actuating member 23 pivots relative to the switch member 24 in pivoting from the position shown in Fig. 1 of the drawings to that shown in Fig. 2, the end 49 of the spring 47 biases the contact means 31 into engagement with the contact means 33 until such time as the lost-motion connection between the actuating member and the switch member is taken up, i. e. until such time as the end 26 of the actuating member strikes the switch member. Similarly, as the actuating member 23 pivots relative to the switch member 24 in pivoting from the position shown in Fig. 3 of the drawings to that shown in Fig. 4, the end 48 of the spring 47 biases the contact means 30 into engagement with the contact means 32 until such time as the lost-motion connection between the actuating member and the switch member is taken up by impact of the end 27 of the actuating member against the switch member.

Thus, irrespective of the direction of pivoting of the actuating member 23, the spring 47 maintains the two contact means which are about to be opened in positive engagement until the impact of the actuating member 23 on the switch member opens such contact means, insuring a clean break with a minimum of arcing. Thus, the spring 47 acts as a resilient means for biasing the two contact means which are about to be opened into positive engagement with each other until the instant they are opened by the actuating member 23.

In the embodiment presently under consideration, the spring 47 cooperates with the switch member 24 to provide a wiping means for absorbing any kinetic energy which tends to cause either of the contact means 30 or 31 to bounce off the corresponding stationary contact means 32 or 33 as it makes contact therewith. As will be apparent, any tendency of one of the contact means 30 or 31 to bounce off its corresponding stationary contact means 32 or 33 requires

pivotal movement of the switch member relative to the actuating member 23. Such pivotal movement of the switch member relative to the actuating member results in sliding movement 5 of the ends 48 and 49 of the spring 47 over a surface of the switch member 24, the kinetic energy tending to produce bouncing of either of the contact means 30 and 31 thus being frictionally absorbed. It will be noted that this energy-absorbing wiping action between the ends 48 and 49 of the spring 47 and the switch member 24 is entirely independent of the contact means 31 to 33 so that it is not affected by pitting of the contact means. Thus, the energy-absorbing action 10 of the wiping means formed by the spring 47 and the switch member 24 is a constant factor, which is an important feature of the invention.

It will be noted that the spring 47 applies a 15 spring force to the switch member 24 which is in addition to the spring force 36 applied thereto by the spring 37 through the actuating member 23. However, the magnitude of the spring force applied by the spring 47 is so small, as compared to the magnitude of the spring force 36, that its 20 effect on the resultant force 45 is negligible.

One more factor to be taken into consideration before discussing the detailed structure and operation of the embodiment in question is that the spring rate of the bimetallic element 43 25 must be such that the input force 41 applied to the actuating member 23 by the bimetallic element does not diminish excessively as the actuating element is pivoted from the position shown in Fig. 1 of the drawings to that shown in Fig. 2, and does not increase excessively as the actuating member is pivoted from the position shown in Fig. 3 to that shown in Fig. 4. In other words, the bimetallic element 43 must have a low spring constant. Otherwise, the offset of the resultant 30 force 45 from the pivot axis might decrease in response to pivoting of the actuating member 23, in which case the device would not operate with as great a snap action, or the resultant force might re-cross the pivot axis, in which case the 35 device would not operate at all.

The snap-action thermostatic switch hereinbefore generally described is illustrated in detail in Figs. 5 to 11 of the drawings. Referring thereto, the supporting structure 21 includes two housings 61 and 62 secured together with screws 63, the housing 61 preferably being formed of electrical insulating material and enclosing the snap-action switch, and the housing 62 enclosing the bimetallic element 43 for operating the snap-action switch. The housings 61 and 62 respectively include removable covers 65 and 66, as best shown in Fig. 6 of the drawings.

Considering first the detailed structure of the snap-action switch in the housing 61, disposed 40 in this housing is a resilient support 67 for the pivoted actuating and switch members 23 and 24, the resilient support 67 having four legs 68 which bear against one wall 69 of the housing 61 which serves as a base on which the snap-action switch is mounted. The resilient support 67 is secured to the base wall 69 by a screw 70 extending through the base wall and threaded into the resilient support, as best shown in Fig. 6. As will be apparent, by varying the extent to 45 which the screw 70 is threaded into the resilient support 67, the spacing between this resilient support and the base wall 69 may be varied. The paired contacts of the stationary contact means 32 and 33 are mounted on the base wall 69 so that varying the spacing between the re-

silient support 67 and the base wall 69 by means of the screw 70 in this manner serves to vary the gaps between the respective contact means 30 and 31 of the switch member 24 and the stationary contact means 32 and 33 when the respective contact means are open. Thus, the resilient support 67 and the screw 70 provide a simple means of setting the gaps between the respective contact means 30 and 31 of the switch member 24 and the stationary contact means 32 and 33, which is an important feature of the invention.

As best shown in Fig. 9 of the drawings, the paired contacts of the stationary contact means 32 and 33 are pressed into openings in the base wall 69 of the housing 61, these contacts being internally threaded to receive screws 73 for attaching electrical conductors thereto.

As best shown in Fig. 6, the resilient support 67 is provided with spaced ears 74 to which the actuating and switch members 23 and 24 are pivotally connected by the pivot means 25, the latter being a pivot pin carried by the ears 74 in the particular construction illustrated. The switch member 24 is preferably formed of electrical insulating material and has connected thereto by a rivet 75 a U-shaped bracket 76 having arms through which the pivot pin 25 extends. The contact bars forming the contact means 30 and 31 of the switch member 24 are loosely connected to the ends of the switch member 24, as by staples 77, to render the contact means 30 and 31 self-aligning with the stationary contact means 32 and 33.

The actuating member 23 is provided with ears 81 through which the pivot pin 25 extends to pivotally mount the actuating member, as best shown in Fig. 6 of the drawings. It will be noted that the length of the ears 81 of the actuating member 23 is greater than that of the arms of the U-shaped bracket 76 which supports the switch member 24, thereby offsetting the actuating member from the pivot pin 25 a greater distance than the switch member 24 to provide the lost-motion connection therebetween hereinbefore described.

As best shown in Figs. 7 and 8, the tension spring 37 for biasing the actuating member 23 in one direction about the axis of the pivot pin 25 is connected to an arm 82 of the actuating member, the spring 37 being pivotally connected to such arm by being hooked through a hole therein. The other end of the spring 37 is hooked through a hole in a link 83, the latter having a hole therein which receives a reduced-diameter portion of a pin 84 carried by the base wall 69 of the housing 61 and extending into such housing.

The hereinbefore described leaf spring 47 for biasing one of the contact means 30 and 31 into engagement with the corresponding one of the stationary contact means 32 and 33 is secured to the actuating member 23 opposite the axis of the pivot pin 25, as by a rivet 87. As best shown in Fig. 7 of the drawings, in order to increase the effective distances of the ends 48 and 49 of the leaf spring 47 from the point of connection of such spring to the actuating member 23, the spring is irregularly shaped, the shape of the spring being approximately that of a block S.

As best shown in Fig. 6 of the drawings, it will be noted that the pivot pin 25 is provided with portions of different diameters which serve to maintain the actuating member 23 and the switch member 24 in their proper relative positions axially of the pivot pin. In the particular con-

struction illustrated, the pivot pin 25 is provided with portions of reduced diameter for engagement with the ears 81 of the actuating member 23, and is provided with one portion of reduced diameter and one portion of larger diameter for engagement with the arms of the U-shaped bracket 76 to which the switch member 24 is connected. One of the arms of this U-shaped bracket is provided with a notch 88 therein for application to a complementary reduced-diameter portion of the pivot pin 25.

Turning now to a consideration of the thermostatic means 42 and the manner in which it operates the snap-action switch, the bimetallic element 43 of the thermostatic means is disposed in the housing 62 and is provided with a free end which bears against a pin 91 for applying the input force 41 to the actuating member 23. This pin extends through registering openings in the covers 65 and 66 of the respective housings 61 and 62 and is seated in a socket 92 in the actuating member 23, as best shown in Fig. 11 of the drawings. The location of the socket 92 is, of course, such that the input force 41 applied to the actuating member 23 through the pin 91 acts in opposition to the tension spring 37, as hereinbefore discussed in detail. A leaf spring 93 riveted or otherwise secured to the cover 66 of the housing 62 bears against a shoulder 94 on the pin 91 to keep the pin seated in the socket 92 even though the pin may be disengaged by the bimetallic element 43 under some temperature conditions. In order to provide the spring 93 with a relatively great effective length in a minimum of space, this spring is made approximately C-shaped, as best shown in Fig. 10 of the drawings.

Considering the supporting means for the bimetallic element 43 with particular reference to Fig. 6 of the drawings, the end of the bimetallic element opposite the free end thereof in engagement with the pin 91 is supported by an adjusting or calibrating screw 96 threaded into a fitting 97 which is secured to the cover 66 of the housing 62. The calibrating screw 96 is provided with a stem 98 which extends through a hole in the bimetallic element, the latter being adapted to seat on a shoulder 99 at the junction of the stem 98 with the head of the calibrating screw. The bimetallic element 43 is supported intermediate its ends by a supporting structure which includes an adjusting screw 102 threaded through the cover 66 of the housing 62 and bearing against one side of the bimetallic element, the adjusting screw having a conical head to provide substantially point contact with the bimetallic element. Such supporting structure also includes a retaining element 103 which is adapted to engage the opposite side of the bimetallic element 43 between the adjusting screw 102 and the calibrating screw 96, the retaining element 103 being carried by the free end of a cantilever spring 104 riveted or otherwise secured to the cover 66 of the housing 62 at 105. It will be noted that the free end of the cantilever spring 104 is provided with a notch 106 therein which receives a reduced-diameter portion of the adjusting screw 102, the spring 104 being biased into engagement with a shoulder 107 on the adjusting screw by its inherent resilience. The adjusting screw 102 carries a pointer 108 which is movable over a dial 109, Fig. 5, formed on the outer surface of the cover 66 of the housing 62. The dial 109 is provided with indicia 110 and is calibrated in terms of temperature.

Considering the operation of the supporting means for the bimetallic element 43, the pointer 108 may be positioned opposite that one of the indicia 110 corresponding to the temperature of the bimetallic element 43 at which the snap-action switch is to operate. Thereafter, the calibrating screw 96 may be adjusted independently of the adjusting screw 102 to vary the position of the free end of the bimetallic element in such a manner as to cause the switch to open either the set of contact means 30 and 32, or the set of contact means 31 and 33, at the temperature corresponding to the position of the pointer 108. After the initial calibration has been made in this manner by means of the calibrating screw 96, the lower end of the bimetallic element 43, as viewed in Fig. 6 of the drawings, is, for all practical purposes, pivotally connected to the supporting structure 21 by the supporting structure comprising the adjusting screw 102 and the retaining element 103. Thus, after the initial calibration has been made, adjusting the bimetallic elements 43 by means of the adjusting screw 102 changes the temperature at which the bimetallic element operates the snap-action switch.

An important feature of the cantilever spring 104 with the retaining element 103 thereon is that it provides means for relieving excessive stresses in the bimetallic element 43, such stresses arising, for example, from temperatures in excess of the normal operating range for which the bimetallic element is designed. As will be apparent, referring particularly to Fig. 6 of the drawings, as the upper or free end of the bimetallic element 43 moves to the left in response to a temperature increase, for example, it acts through the pin 91 to apply the input force 41 to the actuating member 23. Also, the lower end of the bimetallic element 43, as viewed in Fig. 6, exerts a force to the left on the calibrating screw 96. Consequently, the bimetallic element exerts a force to the right on the retaining element 103 of the cantilever spring 104, the magnitude of such force depending upon the temperature to which the device is subjected. Thus, the spring force which the spring 104 exerts to the left against the adjusting screw 102 may be so selected that as the force which the bimetallic element exerts to the right on the retaining element 103 approaches a maximum value below the maximum permissible stress in the bimetallic element, the spring 104 begins to deflect to permit the retaining element 103 to move to the right so that the bimetallic element disengages the adjusting screw 102. In this manner, the spring 104 not only serves as a means of supporting the bimetallic element, but also serves as a means for relieving excessive stresses therein, due, for example, to excessive temperatures, which is an important feature of the invention.

As best shown in Fig. 6 of the drawings, the indicia 110 on the dial 109 are formed by depressions or indentations in the surface of the dial, i. e., in the outer surface of the cover 66 of the housing 62. The pointer 103 is provided with a projection or detent 113 thereon which is engageable with the detent elements provided by the indicia 110. Thus, the detent 113 and the indicia 110 serve as a detent means for retaining the pointer 103, and, consequently, the adjusting screw 102, in various predetermined positions, which is another important feature of the invention.

Referring now to Fig. 12 of the drawings, the

modification illustrated therein is substantially identical to the snap-action thermostatic switch hereinbefore described and will not be considered in detail. The switch illustrated in Fig. 12 is a single-pole, single-throw switch and differs principally from the switch described previously in the omission of the contact means 30 of the switch member 24 and the stationary contact means 32. In place of the contact means 30, the switch member 24 is provided with a button 116 which is engageable with a stop 117 to limit the pivotal movement of the switch member. Also, the end 48 of the leaf spring 47 for biasing the contact means 30 into engagement with the contact means 32 is omitted. In all other respects, the structure of the switch illustrated in Fig. 12 is identical to that described previously, and the operation is also identical.

In Figs. 13 to 20 of the drawings is illustrated a single-pole, single-throw, snap-action thermostatic switch which is similar in structure and operation to that described previously, the embodiment illustrated in Figs. 13 to 20 differing principally in that the structure of the snap-action mechanism is greatly simplified. As a matter of convenience, the general structure and operation of the embodiment of Figs. 13 to 20 will be considered first so that the detailed description of the structure thereof may be more readily understood.

Referring particularly to Figs. 13 to 16 of the drawings, the embodiment illustrated therein includes a supporting structure 121 for an actuating member 123 and a switch member 124, the actuating member 123 being pivotally mounted on the supporting structure 121 by a pivot means 125. The switch member 124 is carried by the actuating member 123 in the particular construction illustrated so that it pivots with the actuating member about the axis of the pivot means 125. The switch member 124 is diagrammatically shown as being disposed in a space 128 between two engaging surfaces of the actuating member 123 so as to provide a lost-motion connection between the actuating member and the switch member. The details of the connection between the actuating member and the switch member will be considered hereinafter.

The switch member 124 serves directly as a contact means in this embodiment, having the form of a contact bar which is adapted to bridge two contacts of a stationary contact means 133 carried by the supporting structure 121. Since this embodiment is a switch of the single-pole, single-throw type, the end of the actuating member 123 opposite that which carries the switch member 124 merely engages a stop means 132 carried by the supporting structure 121.

A tension spring, indicated diagrammatically by the broken line 137, applies a spring force 138 to the actuating member 123 in a direction to bias the switch member 124 into engagement with the contact means 133. The spring 137 is shown as connected to the actuating member 123 intermediate the pivot means 125 and the switch member 124, and as connected to the supporting structure 121 at a point 138. As in the embodiment previously described, the line of the spring 137 is in close proximity to the pivot means 125 so that the length of the spring is substantially unchanged by pivoting of the actuating member 123, whereby the spring force applied to the actuating member is substantially constant as the actuating member pivots between a position wherein one end thereof engages

the stop means 132 and a position wherein the switch member 124 engages the stationary contact means 133.

A variable input force 141 is applied to the actuating member 123 in a direction such that it tends to separate the switch member 124 and the stationary contact means 133, the input force being illustrated as applied by a thermostat means 142 which includes a bimetallic element 143 connected to the supporting structure 121 at 144.

As in the embodiment previously described, the constant spring force and the variable input force may be regarded as a resultant force applied to the actuating member 123, the resulting force being designated by the numeral 145 in Figs. 13 to 16 of the drawings. Referring particularly to Fig. 13, the magnitude of the input force 141 has increased to such an extent that the resultant 145 has swung across the axis of the pivot means 125 and biases the actuating member 123 in a direction to separate the switch member 124 from the stationary contact means 133. In Fig. 14 of the drawings, the actuating member 123 is shown as having pivoted into its other operative position in response to the action of the resultant force 145, the switch member 124 being separated from the stationary contact means 133. It will be noted that, as in the embodiment previously described, the offset of the resultant force 145 from the axis of the pivot means 125 increases as the actuating member 123 pivots, thereby insuring a snap action. Also, because of the lost-motion connection between the actuating member 123 and the switch member 124, the switch member remains in engagement with the stationary contact means 133 until the actuating member has completed part of its pivotal movement so that the actuating member strikes the switch member 124 with an impact force, thereby insuring a clean break of the contacts with a minimum of arcing.

Referring to Figs. 15 and 16, when the input force 141 decreases sufficiently, the resultant force 145 recrosses the axis of the pivot means 125 to restore the actuating member to its original position, thereby causing the switch member 124 to re-engage the stationary contact means 133. Again the offset of the resultant force 145 from the axis of the pivot means 125 increases as the pivotal movement of the actuating member progresses so as to insure a snap action.

Thus, it will be seen that the operation of the embodiment of the invention which is illustrated in Figs. 13 to 20 is substantially identical to that described previously. As in the previous embodiment, it is necessary that the bimetallic element 143 have a relative low spring constant so as to minimize the effects of deflection of the bimetallic element on the input force 141.

As shown diagrammatically in Figs. 13 to 16, a spring 147 acts on the switch member 124 to bias it toward the stationary contact means 133. This insures that the switch member 124 will remain in engagement with the contact means 133 during pivoting of the actuating member 123 from the position shown in Fig. 13 to that shown in Fig. 14 until such time as the lost motion in the connection between the actuating member 123 and the switch member 124 is taken up. Consequently, a sudden break of the contacts with a minimum of arcing is provided, which is an important feature. As will be discussed in more detail hereinafter, the spring 147 also produces a wiping action between the switch member 124 and the stationary contact means 133 so as to

absorb any kinetic energy tending to cause the switch member 124 to bounce off the contact means 133 upon closure.

Considering the structure of the embodiment of Figs. 13 to 20 in more detail with particular reference to Figs. 17 to 20 of the drawings, the supporting structure 121 includes a housing 161 for the snap-action switch and a housing 162 for the thermostatic means 142, the two housings 161 and 162 being secured together by screws 163. The housings 161 and 162 are provided with covers 165 and 166 arranged in face-to-face relation.

The switch embodiment presently under consideration includes a resilient support 167 which corresponds to the previous resilient support 67 and which is provided with legs 168 bearing against a base wall 169 of the housing 161, the resilient support being secured by a screw 170 which serves to vary the deflection of the resilient support so as to vary the gap between the switch member 124 and the stationary contact means 133 when separated. The stationary contact means 133 is carried by the base wall 169 and comprises two contacts pressed into openings in the base wall, these contacts being internally threaded to receive screws 173 for electrical connections to the switch.

The resilient support 167 is provided with ears 174 having openings therethrough which receive tabs 175 on the pivot means 125, the latter, as best shown in Fig. 19, having the form of a thin strip of sheet metal which extends between the ears 174 of the resilient support. The sheet metal strip forming the pivot means 125 is generally channel-shaped to provide rigidity and, as best shown in Fig. 18, is provided with a generally V-shaped opening 176 therethrough. The actuating member 123 is provided with a pair of flanges 177 and 178 which extend along the sides thereof, respectively, the flange 177 having a V-shaped notch 179 therein. The apex of the notch 179 bears against the edge of the V-shaped opening 176 at the apex thereof to provide a pivotal connection between the actuating member 123 and the sheet metal strip forming the pivot means 125. Another, axially aligned, pivotal connection therebetween is provided by engagement of the apex of a V-shaped notch 180 in the other flange 178 on the actuating member 123 with an edge of the sheet metal strip forming the pivot means 125. As best shown in Figs. 17 and 19, the two V-shaped notches 179 and 180 face in opposite directions.

The foregoing pivotal connection between the actuating member 123 and the pivot means 125 renders these elements very easy to assemble. All that is necessary is to insert a portion of the flange 177 of the actuating member through the V-shaped opening 176 until the apex of the notch 179 therein is in engagement with the apex of such opening, and to bring the apex of the notch 180 in the other flange into engagement with the corresponding edge of the sheet metal strip of the pivot means 125.

As best shown in Figs. 17 and 19, the flanges 177 and 178 are provided with notches 181 and 182, respectively, for tabs 183 and 184 on the switch member 124, such tabs being best shown in Fig. 18. As best shown in Fig. 17, when the switch member 124 is in engagement with the contact means 133, the tabs 183 and 184 are spaced from the bottoms of the notches 181 and 182. Consequently, as the actuating member 123 starts to pivot in a direction to separate the switch member 124 from the contact means 133,

the tabs 183 and 184 on the switch member do not engage the bottoms of the notches 181 and 182 until the actuating member has pivoted through a limited angle. Thus, the actuating member engages the switch member with an impact force to provide a sudden disengagement of the switch member from the contact means 133, thereby minimizing arcing.

The spring 147 is generally rectangular, as best shown in Fig. 18, and is provided with tabs 187 and 188 which extend into and engage shoulders 189 and 190 in the notches 181 and 182, respectively, the tabs 187 and 188 also retaining the tabs 183 and 184 on the switch member 124 in the notches 181 and 182 to simplify construction and assembly. The spring 147 is also provided with an intermediate arm 191 having an end 192 which engages the switch member 124, being seated in a socket 193 therein. Thus, the tabs 187 and 188 on the springs 147 bear against the actuating member 123 while the end 192 of the arm 191 bears against the switch member 124 to bias the switch member toward the stationary contact means 133. Thus, the spring 147 serves to maintain the switch member 124 in engagement with the stationary contact means 133 until the lost motion in the connection between the switch member and the actuating member 123 is taken up, thereby insuring a clean break. Moreover, since the spring 147 tends to maintain the switch member 124 in engagement with the stationary contact means 133, it produces a wiping action between the switch member and the contact means upon closure of the switch so that any kinetic energy tending to cause the switch member to bounce off the contact means is absorbed, which is an important feature.

The tension spring 137 acting on the actuating member 123 is pivotally connected thereby by hooking an end of the tension spring through a hole in an arm 196 of the actuating member. The other end of the spring 137 is hooked through a hole in a link 197 having another hole therein which receives a reduced-diameter portion of a pin 198 carried by the base wall 169 of the housing 161.

As in the embodiment previously discussed, the bimetallic element 143 is disposed in the housing 162 and acts on the actuating member 123 through a pin 201 which applies the variable input force 141 produced by the bimetallic element to the actuating member. The pin 201 extends through holes in the covers 165 and 166 into a socket 202 in the actuating member 123, the socket being located on the opposite side of the axis of the pivot means 125 from the point of attachment of the spring 137 to the actuating member in the particular construction illustrated to cause the variable input force 141 to oppose the spring force 146. The pin 201 is biased into the socket 202 by a spring 203 riveted or otherwise secured to the cover 166 of the housing 162 and seated against a shoulder 204 on the pin 201.

The bimetallic element 143 may be supported and adjusted in the same manner as the bimetallic element 43 hereinbefore described. Consequently, the means for supporting and adjusting the bimetallic element 143 are not illustrated in the drawings.

Although I have disclosed exemplary embodiments of my invention herein for purposes of illustration, it will be understood that various changes, modifications and substitutions may be incorporated in the embodiment disclosed with-

out departing from the spirit of the invention.

I claim as my invention:

1. In a snap-action mechanism, the combination of: supporting structure; an actuating member; pivot means providing a pivot axis and connecting said actuating member to said supporting structure for pivotal movement about said pivot axis; an actuated member mounted for pivotal movement relative to said supporting structure about said pivot axis so that both said actuating member and said actuated member are pivotable about the same said pivot axis; means operatively connecting said actuated member to said actuating member so that said actuating member pivots said actuated member upon pivotal movement of said actuating member about said pivot axis, said connecting means including a lost-motion connection between said actuated member and said actuating member so that said actuating member does not pivot said actuated member until a predetermined pivotal movement of said actuating member has occurred, whereby said actuating member applies an impact force to said actuated member; means including a pair of stop means carried by said supporting structure for limiting pivotal movement of said actuating member; means for applying to said actuating member at a point spaced from said pivot axis a substantially constant force tending to produce pivotal movement of said actuating member about said pivot axis in one direction; and an element on said actuating member at a point spaced from said pivot axis and adapted to have applied thereto a variable input force tending to produce pivotal movement of said actuating member in the opposite direction, whereby said actuating member pivots in one of said directions or the other, depending on the magnitude of said variable input force.
2. In a snap-action switch, the combination of: supporting structure; an actuating member pivotally connected to said supporting structure for pivotal movement relative thereto about a pivot axis; a switch member mounted for pivotal movement relative to said supporting structure about the same pivot axis, said switch member being operatively connected to said actuating member so as to pivot therewith about said pivot axis upon pivotal movement of said actuating member about said pivot axis, there being a lost-motion connection between said switch member and said actuating member so that said actuating member does not pivot said switch member until a predetermined pivotal movement of said actuating member has occurred, whereby said actuating member applies an impact force to said switch member to pivot said switch member suddenly, said switch member including a contact means; means including a pair of stop means carried by said supporting structure for limiting pivotal movement of said actuating member and said switch member about said pivot axis, one of said stop means including stationary contact means engageable by said contact means of said switch member; means, including a spring connected to said supporting structure and connected to said actuating member at a point spaced from said pivot axis, for applying to said actuating member at said point a substantially constant force tending to produce pivotal movement of said actuating member about said pivot axis in one direction; and means engaging said actuating member at a point spaced from said pivot axis for applying to said actuating

member a variable input force tending to produce pivotal movement of said actuating member in the opposite direction, whereby said actuating member pivots in one of said directions or the other, depending upon the magnitude of said variable input force.

3. In a snap-action switch, the combination of: supporting structure; an actuating member pivotally connected to said supporting structure for pivotal movement relative thereto about a pivot axis; a switch member mounted for pivotal movement relative to said supporting structure about the same pivot axis, said switch member being operatively connected to said actuating member so as to pivot therewith about said pivot axis upon pivotal movement of said actuating member about said pivot axis, there being a lost-motion connection between said switch member and said actuating member so that said actuating member does not pivot said switch member until a predetermined pivotal movement of said actuating member has occurred, whereby said actuating member applies an impact force to said switch member to pivot said switch member suddenly, said switch member including a contact means; means including a pair of stop means carried by said supporting structure for limiting pivotal movement of said actuating member and said switch member about said pivot axis, one of said stop means including stationary contact means engageable by said contact means of said switch member; means, including a spring connected to said supporting structure and connected to said actuating member at a point spaced from said pivot axis, for applying to said actuating member at said point a substantially constant force tending to produce pivotal movement of said actuating member about said pivot axis in one direction; and thermostatic means responsive to temperature variations and engaging said actuating member at a point spaced from said pivot axis for applying to said actuating member a variable input force tending to produce pivotal movement of said actuating member in the opposite direction, whereby said actuating member pivots in one of said directions or the other, depending on the magnitude of said variable input force.

4. In a snap-action switch, the combination of: supporting structure; an actuating member pivotally connected to said supporting structure for pivotal movement relative thereto about a pivot axis; a switch member operatively connected to said actuating member so as to move therewith about said pivot axis upon pivotal movement of said actuating member about said pivot axis, there being a lost-motion connection between said switch member and said actuating member so that said actuating member does not move said switch member until a predetermined pivotal movement of said actuating member has occurred, whereby said actuating member applies an impact force to said switch member to move said switch member suddenly, said switch member including a contact means; means including a pair of stop means carried by said supporting structure for limiting pivotal movement of said actuating member and said switch member about said pivot axis, one of said stop means including stationary contact means engageable by said contact means of said switch member; means, including a spring connected to said supporting structure and connected to said actuating member at a point spaced from said pivot axis, for applying to said actuating member at said point a substantially constant force tending to produce pivotal movement of said actuating member about said pivot axis in one direction; and means engaging said actuating member at a point spaced from said pivot axis for applying to said actuating member a variable input force tending to produce pivotal movement of said actuating member in the opposite direction, whereby said actuating member pivots in one of said directions or the other, depending upon the magnitude of said variable input force.

pivotal movement of said actuating member about said pivot axis in one direction; and thermostatic means responsive to temperature variations and engaging said actuating member at a point spaced from said pivot axis for applying to said actuating member a variable input force tending to produce pivotal movement of said actuating member in the opposite direction, the angle between said substantially constant force applied to said actuating member by said spring and said variable input force applied to said actuating member by said thermostatic means being greater than 0° and less than 180° so that the resultant of said forces swings from one side of said pivot axis to the other with variations in said variable input force so as to pivot said actuating member in one of said directions or the other, depending upon the magnitude of said variable input force.

5. A snap-action switch as defined in claim 4 wherein said spring is a coil spring extending along a line which is in close proximity to said pivot axis so that the length of said spring remains substantially constant during pivotal movement of said actuating member about said pivot axis, whereby to maintain the force applied to said actuating member by said spring substantially constant.

6. In a snap-action switch, the combination of: supporting structure; an actuating member pivotally connected to said supporting structure for pivotal movement relative thereto about a pivot axis; a switch member operatively connected to said actuating member so as to move therewith about said pivot axis upon pivotal movement of said actuating member about said pivot axis, said actuating member being pivotally connected to said supporting structure for pivotal movement about said pivot axis by a pivot means and said switch member being pivotally connected to said supporting structure for pivotal movement about said pivot axis by the same pivot means, there being a lost-motion connection between said switch member and said actuating member so that said actuating member does not move said switch member until a predetermined pivotal movement of said actuating member has occurred, whereby said actuating member applies an impact force to said switch member to move said switch member suddenly, said switch member including a contact means; means including a pair of stop means carried by said supporting structure for limiting pivotal movement of said actuating member and said switch member about said pivot axis, one of said stop means including stationary contact means engageable by said contact means of said switch member; means, including a spring connected to said supporting structure and connected to said actuating member at a point spaced from said pivot axis, for applying to said actuating member at said point a substantially constant force tending to produce pivotal movement of said actuating member about said pivot axis in one direction; and means engaging said actuating member at a point spaced from said pivot axis for applying to said actuating member a variable input force tending to produce pivotal movement of said actuating member in the opposite direction, whereby said actuating member pivots in one of said directions or the other, depending upon the magnitude of said variable input force.

7. A snap-action switch as defined in claim 6 wherein said actuating member and said switch member are offset laterally with respect to each other so that said actuating member may pivot

relative to said switch member about said pivot axis so as to produce said lost-motion connection between said actuating member and said switch member, said actuating member having ends on opposite sides of said pivot axis which are adapted to engage said switch member after pivotal movement of said actuating member relative to said switch member through a limited angle to communicate pivotal movement of said actuating member to said switch member.

8. A snap-action switch as defined in claim 2 wherein said switch member is connected to said actuating member by said lost-motion connection at a point spaced from said pivot axis.

9. A snap-action switch as defined in claim 2 including wiping means, comprising a pair of relative slidable elements, for absorbing any kinetic energy tending to cause said contact means of said switch member to bounce off said stationary contact means, said kinetic energy being frictionally absorbed by said relatively slidable elements.

10. A snap-action switch as defined in claim 9 wherein one of said elements of said wiping means is carried by said actuating member and slidably engages a surface of said switch member, said surface of said switch member forming the other of said elements of said wiping means.

11. A snap-action switch as defined in claim 10 wherein said one element of said wiping means includes a leaf spring, rigidly connected to said actuating member and engaging said surface of said switch member, for biasing said contact means of said switch member toward said stationary contact means, said leaf spring maintaining said contact means of said switch member in engagement with said stationary contact means during pivotal movement of said actuating member in a direction to separate the two contact means until such time as the lost motion between said actuating member and said switch member is taken up.

12. A snap-action switch as defined in claim 2 including resilient means carried by said actuating member and engaging said switch member for biasing said contact means of said switch member toward said stationary contact means, whereby said resilient means maintains said contact means of said switch member in engagement with said stationary contact means during pivotal movement of said actuating member in a direction to separate the two contact means until such time as the lost motion between said actuating member and said switch member is taken up.

13. In a snap-action switch, the combination of: supporting structure; stationary contact means carried by said supporting structure; a switch member movable relative to said supporting structure and including contact means engageable with said stationary contact means; means movably connecting said switch member to said supporting structure, including pivot means providing a pivot axis about which said switch member is pivotable relative to said supporting structure; and wiping means, including an element slidably engaging said switch member, for absorbing any kinetic energy tending to cause said contact means of said switch member to bounce off said stationary contact means, said element of said wiping means comprising a leaf spring which is pivotally connected to said supporting structure by said pivot means and which is offset laterally from said switch member to provide a lost-motion connection therebetween, said leaf spring having an end in slidable engage-

ment with said switch member, said snap-action switch further including means for biasing said end of said leaf spring into slidable engagement with said switch member.

5 14. A snap-action switch as defined in claim 13 wherein said contact means of said switch member is disposed on one side of said switch member and wherein said end of said leaf spring engages the opposite side of said switch member 10 adjacent said contact means thereof so that the leaf spring biases said contact means of said switch member toward said stationary contact means.

15 15. A snap-action switch according to claim 2 wherein said supporting structure includes a base which carries said stationary contact means and includes a resilient support which carries said actuating member and said switch member, said snap-action switch further including adjusting 20 means engaging said base and said resilient support for flexing said resilient support to vary the gap between said stationary contact means and the contact means of said switch member when the two contact means are separated.

25 16. In a snap-action switch, the combination of: supporting structure including a base and a resilient and flexible support connected to said base; stationary contact means carried by said base; a switch member pivotally connected to 30 said resilient support and including contact means engageable with said stationary contact means; means for pivoting said switch member between a position wherein the two contact means are separated and a position wherein the 35 two are in engagement; and adjusting means engaging said base and said resilient support for flexing said resilient support to vary the gap between the two contact means when the two are separated.

40 17. A snap-action mechanism as defined in claim 1 wherein said actuating member is provided with oppositely facing notches therein along said pivot axis, said pivot means comprising an element having edges disposed in said notches, respectively.

45 18. In a snap-action mechanism, the combination of: supporting structure; an actuating member; pivot means providing a pivot axis and connecting said actuating member to said supporting structure for pivotal movement about said pivot axis; an actuated member; means operatively connecting said actuated member to said actuating member so that said actuating member moves said actuated member upon pivotal movement of said actuating member about said pivot axis, said connecting means including a lost-motion connection between said actuated member and said actuating member so that said actuating member does not move said actuated member until a predetermined pivotal movement of said actuating member has occurred, whereby said actuating member applies an impact force to said actuated member; means including a pair of stop means carried by said supporting structure for limiting pivotal movement of said actuating member; means for applying to said actuating member at a point spaced from said pivot axis a substantially constant force tending to produce pivotal movement of said actuating member about said pivot axis in one direction; and an element on said actuating member at a point spaced from said pivot axis and adapted to have applied thereto a variable input force tending to produce pivotal movement of said actuating member in the opposite direction, the angle between said substan-

tially constant force applied to said actuating member and said variable input force applied thereto being greater than 0° and less than 180° so that the resultant of said forces swings from one side of said pivot axis to the other with variations in said variable input force so as to pivot said actuating member in one of said directions or the other, depending upon the magnitude of said variable input force.

19. In a snap-action switch, the combination of: supporting structure; an actuating member pivotally connected to said supporting structure for pivotal movement relative thereto about a pivot axis; a switch member pivotally connected to said supporting structure for pivotal movement relative thereto about the same pivot axis, said switch member being operatively connected to said actuating member so as to pivot therewith about said pivot axis upon pivotal movement of said actuating member about said pivot axis, 20 there being a lost-motion connection between said switch member and said actuating member so that said actuating member does not pivot said switch member until a predetermined pivotal movement of said actuating member has occurred, said switch member including a contact means; a stationary contact means carried by said supporting structure and engageable by said contact means of said switch member upon pivotal movement of said actuating member and 30 said switch member in a direction to move said contact means of said switch member toward said stationary contact means; and wiping means, comprising a pair of relatively slidible elements, for absorbing any kinetic energy tending to cause 35 said contact means of said switch member to bounce off said stationary contact means, one of said elements of said wiping means being carried

by said actuating member and slidably engaging a surface of said switch member, said surface of said switch member forming the other of said elements of said wiping means.

5 20. A snap-action switch as defined in claim 19 wherein said one element of said wiping means includes a leaf spring, rigidly connected to said actuating member and engaging said surface of said switch member, for biasing said contact means of said switch member toward said stationary contact means, said leaf spring maintaining said contact means of said switch member in engagement with said stationary contact means during pivotal movement of said actuating member in a direction to separate the two contact means until such time as the lost motion between said actuating member and said switch member is taken up.

ALBERT E. BAAK.
